UNITED STATES PATENT OFFICE.

GEORGE V. GEIS, OF DAYTON, OHIO.

DESIGN FOR A PAN-BISCUIT.

50,810.

Specification for Design.

Patented May 22, 1917.

Application filed February 26, 1916. Serial No. 80,745. Term of patent 7 years.

To all whom it may concern:

Be it known that I, GEORGE V. GEIS, a citizen of the United States, residing at Dayton, in the county of Montgomery and State of Ohio, have invented a new, original, and ornamental Design for a Pan-Biscuit, of which the following is a specification, reference being had to the accompanying drawing, forming a part thereof.

The figure is a perspective view of a pan biscuit showing my new design.

I claim:

The ornamental design for a pan biscuit substantially as shown.

GEORGE V. GEIS.
